Filed Feb. 2, 1965, Ser. No. 83,666

Term of patent 14 years

(Cl. D26—13)

FIG. 1

FIG. 2

FIG. 4

FIG. 3

FIG. 5

FIG. 6

FIG. 1 is a perspective view of a housing for remote student controls of a language laboratory showing my new design, this view being taken from the front and somewhat above and to the left of the base panel surface.

FIG. 2 is a plan view of the inclined panel surface of the base of FIG. 1.

FIG. 3 is an end view of the base of FIG. 2.

FIG. 4 is a rear view of the base of FIG. 2.

FIG. 5 is a sectional view taken along the line 5—5 of FIG. 2.

FIG. 6 is a sectional view taken along the line 6—6 of FIG. 4.

The dominant features of my new design are shown in solid lines in the drawing. The control knobs, etc. are shown in broken lines in FIGS. 1 and 2 and have been omitted from FIGS. 5 and 6 for convenience in illustration.

I claim:

The ornamental design for a housing for remote student controls of a language laboratory, as shown and described.
